UNITED STATES PATENT OFFICE.

JOHN H. GAVIN; OF CHICAGO, ILLINOIS, ASSIGNOR TO THE L. WOLFF MANUFACTURING COMPANY, OF SAME PLACE.

DESIGN FOR A BRACKET.

SPECIFICATION forming part of Design No. 23,780, dated October 23, 1894.

Application filed September 28, 1894. Serial No. 524,405. Term of patent 14 years.

To all whom it may concern:

Be it known that I, JOHN H. GAVIN, a citizen of the United States, residing at Chicago, in the county of Cook and State of Illinois, have invented and produced a new and original Design for Brackets for Supporting Basins, Sinks, Tanks, and other Articles, of which the following is a specification, reference being had to the accompanying drawing, forming a part thereof.

The drawing shows in perspective a right angle bracket embodying my design.

The leading feature of my design consists, in connection with the two right angle arms A A' of the bracket, of the novel shape and configuration of the brace work filling the angle of the bracket; the same comprising a circular ring B at the angle of the bracket furnished with a blade shaped radial arm b, two ogee curved arms b' b' and two curved arms b² b² terminating in scrolls b³ b³ near the center of the circular ring, from the angle of which scrolls b³ b³ spring three small leaf or

petal shaped ornamentations b⁴ b⁴ b⁴; combined with a double headed bundle or sheaf C at the arc of the ring B diametrically opposite the angle of the bracket, and a double ogee curved brace D D extending from the double bundle C to the two arms A A' of the bracket and furnished with scrolls d d and d' d', the scrolls d d being connected with the double bundle C by curved arms F F as illustrated in the drawing, so that the curved arms D F and the arc of the ring B have somewhat the appearance of three curved stalks springing from the head of the bundle C. The double bundle C is furnished with a band c at its middle.

I claim—

The design for a bracket, herein shown and described.

JOHN H. GAVIN.
